UNITED STATES PATENT OFFICE.

FREDERICK MAYO, OF ZANESVILLE, OHIO, ASSIGNOR TO HIMSELF AND
FRANK J. KORTE, OF SAME PLACE.

MILLSTONE-DRIVER.

SPECIFICATION forming part of Letters Patent No. 242,098, dated May 24, 1881.

Application filed June 19, 1880. (No model.)

To all whom it may concern:

Be it known that I, FREDERICK MAYO, of Zanesville, in the county of Muskingum and State of Ohio, have invented new and useful 5 Improvements in Millstone-Drivers, of which the following is a specification.

Figure 1 is a bottom view of my invention detached from the spindle and stone. Fig. 2 is a vertical view of the same, partly in section, 10 in place on the spindle.

Similar letters of reference indicate corresponding parts.

Much difficulty has been experienced in running millstones from backlash from the face 15 of the stones getting out of relative position, and consequently irregular grinding. To overcome these difficulties is the principal object of my improvements.

My invention consists in a millstone-driver 20 having arms with adjustable springs, to compensate for backlash, to prevent irregularities in the running of the stone and insure the best results otherwise.

In the form of construction shown the driver 25 has three arms, B C D, projecting from a center piece, E, having mortise *a* adapted to the shoulder *b* on the spindle *F*. Each of the arms has a top spring, *c*, bolted or otherwise secured to the arm, and adjustable by set-screw *d*. Each 30 of the arms also has a side spring, *e*, adjustable by set-screw *f*. The bail also has three arms, G H I, projecting from a center piece, K, having a recess, *g*, corresponding with and to rest

on the conical point *h* of the spindle. Each of the arms G H I has a cap or recess, *i*, which 35 receives the ends of the arms B C D and the ends of the springs connected thereto.

The stones are not shown; but when properly in position in relation to the driver the relative position required for uniform grinding can be 40 kept adjusted by the arms and top springs, and the backlash can be counteracted by the arms and side springs.

The details of construction can be varied within the scope of my improvements. The 45 arms G H I may curve inward and the adjusting-screws *d* be tapped into said arms, as shown by dotted lines.

I am aware that it is not broadly new to take up the backlash with side springs where 50 the stone is held in horizontal position simply by gravity; but I find that gravity alone does not attain this object when the stone is in motion, and for this reason I have employed the top springs, *c*, arranged as above described. 55

What I claim as new and of my invention is—

The top springs, *c*, combined with the arms B C D, having intermediate springs, *e*, and arms G H I, having caps or recesses *i*, all arranged 60 in a millstone-driver, as and for the purpose specified.

FREDERICK MAYO.
